UNITED STATES PATENT OFFICE.

GEORGE C. GARDNER, OF CHICAGO, ILLINOIS.

DESIGN FOR A CASING MEMBER FOR SLIDING-DOOR SUPPORTS.

SPECIFICATION forming part of Design No. 31,088, dated June 27, 1899.

Application filed April 2, 1897. Serial No. 630,483. Term of patent 7 years.

To all whom it may concern:

Be it known that I, GEORGE C. GARDNER, a citizen of the United States, residing at Chicago, in the county of Cook and State of Illinois, have invented and produced a new and original Design for a Casing Member for Sliding-Door Supports, of which the following is a specification, reference being had to the accompanying drawings, forming a part thereof.

10 Figure 1 is a view of one side of the member involving the novel design. Fig. 2 is a like view of the opposite face of the same member. Fig. 3 is view looking from the right in Fig. 1. Fig. 4 is a section on the line 15 4 4, Fig. 1.

As shown in the drawings, the faces of the body of the member correspond, bearing to each other the relation of relief and intaglio. The face shown in Fig. 1 has a plane central portion, with two parallel boundary-lines whose corresponding ends are connected by circular curves, and surrounding this portion is a uniform raised portion whose surface is approximately semicircular in cross-section 25 at all points. The same part as seen in Fig. 2 has a depression or groove a surrounding

the plane central portion a^2 , and surrounding this depression, except upon the lower side, is a narrow marginal edge a' in the plane of the face of the part a^2 . At the lower side of 30 the body portion projects a lip a^3 , parallel to the plane of the part a^2 , but in a plane passing through the depression a , so that were the face seen in Fig. 2 laid upon a plane surface there would be between that surface and the 35 lip a broad passage leading to the depression a . At each end of the body portion, in a plane perpendicular to the plane of the part a^2 and passing between the latter and the lip, is an ear or flange a^5 , and filling the upper angle 40 made by each flange with said body portion is a small web a^4 .

Having described my invention, what I claim is—

The design for a casing member for sliding- 45 door supports substantially as shown and described.

GEORGE C. GARDNER.
